UNITED STATES PATENT OFFICE.

JAMES DOHERTY, OF CHICAGO, ILLINOIS; ELLA MAUD DOHERTY AND JAMES RUSSELL DOHERTY EXECUTORS OF SAID JAMES DOHERTY, DECEASED.

SECTIONAL FURNACE.

Application filed March 21, 1923. Serial No. 626,484.

My invention relates to a sectional furnace of known type, which is made up of an assembled series of hollow water-containing sections and in which it is sought to procure 5 complete combustion and to render the furnace smokeless by the introduction of auxiliary air, the structure and objects thus generally recited being familiar in this art. My invention is concerned with the means 10 for bringing about these results in the most effective manner, that is, for introducing the air at the proper place and in the best way and at a proper temperature, and involves associating the auxiliary air passage or pas- 15 sages in a furnace of the type stated with a water-containing bridge wall or with a water-containing baffle wall in advance of the bridge wall and in the preferred form with both, and in providing a supplementary 20 mixing and combustion chamber formed in or by adjacent sections and located above the fuel space and preferably, at least in part over it, and just beyond the point of introduction of the auxiliary air. My invention 25 also lies in the structure of certain sections, and in other features hereinafter pointed out.

Referring to the drawings,

Fig. 1 is a side elevation partly in vertical 30 section of a furnace embodying my invention;

Fig. 2 is a front elevation partly in section on line II-II of Fig. 1;

Fig. 3 is a perspective view of the angle 35 bar completing one of the auxiliary air passages;

Fig. 4 is a horizontal section on the line 40 IV-IV of Fig. 2, and

Fig. 5 is a detail section showing the es- 45 sential parts of the preferred form of my invention.

The furnace in which the invention is 50 illustrated is made up of a series of hollow water-containing sections 1, bolted together 55 in the customary way and suitably supported on a base comprised of the side members 2 which are connected by front and rear transverse plates 3 and 4, and by an intermediate transverse division plate 5 which 60 latter forms the rear of the ash pit. The front plate 4 carries the usual ash-pit door and damper arrangements, and fuel-feed and flue clean-out doors are provided as usual in the front section. The sections are 65 interiorly shaped to form the firebox 6, rear

flue space 7 in communication therewith, upper forward and return flues 8 and 9, and the fire-box has a perforate grate, as indicated. Two of the intermediate sections, which I have designated respectively as 1^a and 1^b embody the novel features, which by their presence and cooperation in the furnace combine to produce the results above alluded to. The section 1^a is shaped to form the fire-bridge or rear wall 11 of the firebox, being as heretofore stated hollow and water-containing and defining by its upper edge the underside of the outlet opening of the supplementary combustion chamber 17 which will be more fully described herein- 60 after. This section is further provided with means for delivering air athwart the current of burning gases as it passes from the fire-box to the rear flue space 7. Such means consists of an air passage located near the upper part of the bridge wall and is constituted by a rabbet recess 12 formed in the cast bridge wall 11, preferably along its top front corner, and covered by a separately made member which most conveniently 65 takes the form of an angle bar 13, secured removably in place by bolts, as indicated, or otherwise. This bar is provided with a continuous slot or a series of air delivery open- 70 ings 14 in its front or vertical flange, and the passage formed between it and the bridge wall is open to atmosphere at its ends, through suitable openings cast in the side 75 portions of the section 1^a as will be understood. This section 1^a also, has a water-con- 80 taining wall portion 15 directly above the fire bridge 11 and air passage 12 which co- 85 operates with the latter members to complete the outlet from the supplementary chamber 17 above referred to. The furnace section 1^b immediately in advance of the bridge wall section 1^a is formed with a de- 90 pending water-cooled baffle wall 16, the form of which may vary but which in Fig. 1 is an unbroken vertical water-curtain depend- 95 ing to about the level of the top of the fire bridge or slightly lower, and being for- 100 wardly spaced therefrom so as to form there- 105 with an upward passage for the fire gases. With the adjacent parts of section 1^a, this section 1^b and its water curtain 16 also form a space 17 which may be termed a sup- 110 plementary combustion chamber and which is of relatively small capacity as compared with the firebox, being located adjacent the

top of the firebox, that is, between the firebox and the overhead flues. It will be noted that in addition to the main supply of combustion-supporting air entering through the 5 perforate grate an auxiliary supply is also admitted through the air passage 12 and its distributing outlets 14, both under the pull of the chimney draft. The auxiliary air is thus delivered with considerable velocity 10 forwardly into the current of burning gases passing the bridge wall and being heated by contact with the angle bar 13, has the effect of increasing and quickening the combustion reaction. The effect of the pocket or space 15 formed by the supplementary combustion chamber 17 causes a more thorough intermixing of the air with the fire gases than would otherwise occur, there being a double change in direction of the gases during their 20 passage into, through and out of said chamber with corresponding opportunity for more perfect combustion and a more efficient utilization of the heat released. It will be understood, however, that there is no intention 25 to imply any limitation of the units 1^a or 1^b to the particular forms which they have in the furnace illustrated, it being sufficient that they retain characteristics insuring the attainment of the objects of the invention 30 in a substantially similar way.

In the form illustrated in Fig. 5, the section 1^a is the same as in Fig. 1. Section 1^b is however modified by providing the rear side of the depending wall 16 with a water- 35 cooled ledge or shelf 18 adjacent its lower edge. This shelf runs across the furnace and together with a removable cover member 19, preferably a removable angle bar exactly the same as bar 13 and interchangeable 40 with it, forms an auxiliary air passage to each end of which air is admitted from atmosphere through openings cast in the sides of this section as in the case of section 1^a. This passage is preferably situated directly 45 opposite the other air passage 12 and like the latter is formed by the cooperation of the angle bar with a shouldered part of the casting. Its purpose is not so much to admit a larger amount of air to the fire gases, 50 as to provide better distribution of the limited amount that is needed for the unconsumed fuel. Regulation of the amount admitted is provided by the small dampers 20 carried in the bushings 21 inserted in the ends 55 of both air passages. It will be apparent that the fire-gas flow from the fire-box will be thoroughly mixed with well-heated auxiliary air, penetrating and mixing with it from opposite sides and that the chamber 60 17 affords opportunity, as before, for better mixing of the gases with the air, and it will be understood that by proper adjustment of the air supply the furnace may be readily operated on bituminous coal with 65 the intense smokeless combustion effect that

is characteristic of furnaces of this type,
Claims—

1. A sectional furnace composed of an assembled series of cast hollow water-containing sections having a grate and forming a 70 firebox and having a hollow water-containing baffle wall depending into the firebox, and a hollow water-containing bridge wall in rear of said baffle wall and horizontally spaced therefrom and between which and 75 said baffle wall fire gases pass, said bridge wall having adjacent its front top corner an air passage having a forwardly facing outlet whereby air is delivered forwardly athwart the fire-gas flow. 80

2. A sectional furnace made up of an assembled series of transverse hollow water-containing sections and having a grate and firebox, two adjacent sections of said series forming respectively a water-containing 85 baffle wall in the firebox and a water-containing bridge wall in rear thereof, and air delivering means associated with the rear of the baffle wall and with the front of the bridge wall and extending transversely of 90 the furnace and each having means for distributing and delivering auxiliary air to the fire-gas flow. 95

3. A sectional furnace made up of an assembled series of hollow water-containing sections and having a grate and a firebox and a water-containing baffle wall therein having on its rear side adjacent its bottom, a rearwardly projecting water-containing 100 ledge, removably air delivery means associated with said ledge for forming an air passage along the same, through which auxiliary air is distributed to the fire-gas flow, and a bridge wall adjacent the baffle wall. 105

4. A sectional furnace composed of an assembled series of cast hollow, water-containing sections, having a grate and forming a firebox, two of said sections being adjacent and providing respectively a water-containing 110 baffle wall depending into the firebox and a water-containing bridge wall upstanding in rear of and above said baffle wall and spaced therefrom and forming therewith an upward passage for the fire-gas flow, said walls having opposed portions of less thickness than the adjacent portions, thereby forming shoulders, and means associated with said reduced portions and shoulders forming therewith transverse air delivery 115 passages, said means being adapted for heating and mixing air with the fire-gas flow. 120

5. A sectional furnace made up of an assembled series of hollow water-containing sections and having a grate and a firebox, 125 a water-containing baffle wall depending into the firebox and having at its rear side adjacent the bottom a water protected ledge extending crosswise of the furnace and removable means for forming an air passage along 130 135

5 said ledge having a rearwardly directed air distributing outlet therefrom, a hollow water-containing bridge wall in rear of said baffle wall and spaced therefrom and between which and said baffle wall the fire gases pass, an air delivery passage adjacent the top front corner of the bridge wall and having forwardly delivering air openings, whereby auxiliary air is distributed through 10 said outlet openings and delivered rearwardly and forwardly respectively across and into the fire gas flow.

6. A sectional furnace composed of an assembled series of cast hollow water-containing sections, having a grate and forming a firebox and having a water-containing baffle wall depending into the fire-box, a water-containing bridge wall upstanding in rear of and above said baffle wall and spaced 15 therefrom and forming therewith an upward passage for the fire-gas flow, the front of said bridge wall and the rear of said baffle wall being provided with opposed air delivery passages extending transversely 20 along said walls and interchangeable angle bars provided with delivery openings in their opposed faces and completing the respective delivery passages whereby air is delivered to front and rear across the fire 25 gas flow.

7. A sectional furnace made up of an assembled series of cast hollow water-containing sections having spaces constituting respectively a firebox provided with a bridge 30 wall, and a supplemental combustion chamber having a depending wall in front of and spaced from the bridge wall, said supplemental combustion chamber being located adjacent the upper part of the firebox near the 35 bridge wall and in communication with the firebox adjacent the bottom of the chamber by a vertical passage between the depending wall and the bridge wall, the outlet of the chamber being a horizontal passage and said 40 chamber having a downwardly projecting water-cooled wall which assists in defining the outlet, and means for delivering auxiliary air to the fire gas flow adjacent the inlet of the chamber, the construction described furnishing a pocket in the upper part of the 45 chamber and by reason of the relative arrangement of inlet and outlet specified insuring change of direction and consequently mixing of the fire gases and auxiliary air as 50 they pass through the chamber.

8. A sectional furnace made up of an assembled series of transverse hollow water-containing sections having a grate and forming a firebox and flue space in rear of and 55 in communication therewith, and overhead return flues above said firebox and flue space and in communication with the latter, intermediate sections forming by water-cooled walls a supplemental combustion chamber 60 defined in part by a depending water-cooled

70 wall in front of and spaced from the bridge wall, said chamber overhanging the rear part of the firebox, having a downwardly opening fire gas inlet therefrom and located near the level of the firebox roof and between the firebox and flue space and communicating with the firebox on the one hand and with the flue space on the other by a restricted opening, and means for distributing and delivering air to the fire gases as they pass from the firebox up into the supplementary combustion 75 chamber.

9. A sectional furnace composed of a series of hollow water-containing sections having a grate and forming a firebox, a hollow water-containing baffle wall depending into the firebox near the rear thereof, a hollow water-containing bridge wall in rear of said baffle wall and horizontally spaced therefrom and between which and said baffle wall the fire 80 gases flow, a supplementary water-backed combustion chamber of relatively moderate dimensions as compared with the firebox and in communication therewith located immediately in rear of said baffle wall and above 85 the fuel space, and an air delivery passage associated with the bridge wall adjacent its top and extending crosswise of the furnace for delivering auxiliary air across the fire 90 gas flow as it passes into said supplementary 95 combustion chamber.

10. A sectional furnace made up of an assembled series of cast hollow water-containing sections and having a grate and a firebox, a hollow water-containing baffle wall 100 depending into the firebox, and having at its rear side adjacent the bottom thereof a water protected ledge and removable means forming an air passage along said ledge for auxiliary air having a rearwardly opening outlet, 105 a hollow water-containing bridge wall upstanding in rear of said baffle wall and spaced therefrom and forming therewith an upward passage for the fire-gas flow, an air delivery passage adjacent the top of the bridge wall 110 at its front side for delivering auxiliary air, having forwardly facing outlets, and a supplementary water-cooled combustion chamber of relatively moderate dimensions compared with the firebox and in communication therewith through the space between the baffle wall and bridge wall, said supplementary combustion chamber being immediately in rear of said baffle wall.

11. In a sectional furnace composed of a series of transverse hollow water-containing sections, a supplemental combustion chamber having restricted inlet and outlet and formed by two adjacent sections said supplemental combustion chamber extending across the furnace and having water-containing walls, and means associated with at least one of said sections for delivering air adjacent the inlet of said chamber.

12. In a sectional furnace, a cast hollow

water-containing section having at its lower part a hollow water-containing bridge wall, a fire-gas passage above the same, overhead flue openings separated from said fire-gas opening by a transverse water-containing portion having a downwardly projecting wall over the bridge wall, defining therewith the fire gas passage, of less depth than the bridge wall and displaced rearward of

its front face to provide fire gas space over 10 the bridge wall, said bridge wall having associated therewith means forming therewith a forwardly delivering air duct extending across the section.

In testimony whereof, I have signed this 15 specification.

JAMES DOHERTY.
